UNITED STATES PATENT OFFICE.

MARION M. MILLER, OF PITTSBURG, PENNSYLVANIA, ASSIGNOR OF ONE-HALF TO ARTHUR B. BELLOW, OF PITTSBURG, PENNSYLVANIA.

AUTOMATIC ADJUSTABLE BRAKING DEVICE.

SPECIFICATION forming part of Letters Patent No. 728,174, dated May 12, 1903.

Application filed September 27, 1902. Serial No. 125,036. (No model.)

To all whom it may concern:

Be it known that I, MARION M. MILLER, of Pittsburgh, Allegheny county, Pennsylvania, have invented a new and useful Automatic

5 Adjustable Braking Device, of which the following is a full, clear, and exact description, reference being had to the accompanying drawings, forming part of this specification, in which—

10 Figure 1 is a side elevation showing a hopper-car provided with my improved braking system. Fig. 2 is a top plan view of the same with the floor broken away, and Figs. 3 and 4 are detail views of parts hereinafter referred to.

15 My invention relates to that class of railway-brakes wherein automatic means is provided to adjust the power of the brake for different loads; and it is designed to provide 20 a simple and effective system of this character which may be applied to hopper-cars.

In the drawings, I show a hopper-car where the brake-cylinder is located beneath the overhanging end beneath the inclined floor 25 portion of the car-body at one end.

5' is the braking-cylinder. 6' is the push-rod, 7' the cylinder-lever, extending vertically in this case, and 10' the connecting-rod, leading to the floating lever, 30 which is connected to the brake-levers. I provide the cylinder-lever 7' at its upper end with a bent extension 30, having a longitudinal slot 31, through which extends a pin 32, passing through the slotted ears of a bracket 33, secured to an end post of the car-frame. Two links 34 are pivoted to the ends of the pin 32 outside the bracket-ears, and these links are pivoted at their upper end to a lever 35, whose other end is rigidly secured to 35 a rock-shaft 36, having also secured near its other end a lever 37. A link 38 pivotally connects the lever 37 to one arm 39 of a bell-crank lever, whose other arm 40 is pivotally connected with a rod 41, whose other end is 40 pivoted to the bracket 15', secured to the transom 16'. The shaft 36 and the shaft for

the bell-crank 39 are both mounted in stationary bearings, shown in brackets 42, secured to the sloping bottom 43 of the hopper-body.

50 When the sloping bottom is deflected under the load, the several parts are brought from the position shown in full lines down to that shown in dotted lines in Fig. 4, thus shifting the fulcrum-point of the cylinder-lever 7', 55 which is at its end.

It will be understood that it is desirable to provide a point of support for the apparatus which is fixed relatively to the track, so that the car-body will move relatively to the fixed 60 point. Hence in the case of a pedestal-truck, where the transom moves up and down relatively to the track, I would preferably use as a fixed point of support some portion of the journal-box for the car-wheel axle, while 65 the movable point relative to this fixed point may be either some part of the car-body or of the truck.

The advantages of my invention will be obvious to those skilled in this art. The difficulties heretofore experienced by reason of the incorrect braking power of a hopper-car when loaded proportionate to the car when light, and vice versa, are overcome, and the change in load automatically changes the 75 braking power, thus giving the desirable amount of power according to the load. The locking of the wheels, on the one hand, and the insufficient braking of the car, on the other hand, are prevented, and the change 80 of the braking power is not dependent on the efficiency or intelligence of the trainmen.

Variations may be made in the form and arrangement of the connections by which the vertical movement of the car shifts the connecting-rod, as well as in the brake connection and other parts, without departing from my invention.

I claim—

1. A hopper-car having a brake-cylinder 90 with connections located under the sloping end floor, and an adjusting apparatus secured

to said sloping end floor and arranged to change the braking power under deflection by the load; substantially as described.

2. A hopper-car having braking mechanism located beneath the sloping end floor of the hopper, a cylinder-lever having a fulcrum-point at its end, forming a part of the mechanism, and connections operated by the deflection of the floor and arranged to shift

said end fulcrum of the lever; substantially as described.

In testimony whereof I have hereunto set my hand.

MARION M. MILLER.
